UNITED STATES PATENT OFFICE.

LE ROY S. WHITE, OF WATERBURY, CONNECTICUT, ASSIGNOR TO BROWN & BROTHERS, OF NEW YORK, N. Y.

DESIGN FOR SPOONS AND FORKS.

SPECIFICATION forming part of Design No. 12,124, dated January 11, 1881.

Application filed January 9, 1880. Term of patent 14 years.

To all whom it may concern:

Be it known that I, LE ROY S. WHITE, of Waterbury, in the county of New Haven and State of Connecticut, have originated and produced a new Design for Forks, Spoons, and other Articles of Table-Ware, of which the following is a specification.

My design, which may be embodied in handles and other articles of table-ware, as well as in forks and spoons, is clearly illustrated in the accompanying drawings, in which—

Figure 1 represents a face view of a fork of my design. Fig. 2 represents a view of the back thereof. Fig. 3 represents a front view of the bowl and a portion of the stem or shank of a spoon, and Fig. 4 a back view thereof.

One prominent feature of my design consists in the continuity of the curved outline of the outer edge of the bowl A of the spoon or 20 the body B of the fork, as shown at *a a* in Figs. 2 and 4, where it will be seen that the rounded external contour-line of the body B and of the bowl are continued in unbroken lines across the back of the shank or stem C.

25 The handle has several peculiarities, which I will now proceed to describe. The shank or stem C, at its junction with the bowl, is ornamented with a striated bead-like projection, *b*, above which its profile is gradually first contracted and then enlarged with a hollow curved contour, as indicated at *c c*, to an abrupt ornamental protuberance, *e*, at the connection of the shank or stem with the head or stock E D. The head or stock E D swells upward with 35 a concave profile, as indicated at *f f*, nearly to the top, its extreme width being very near the tip *d*, and the contraction between the widest part and the tip being made with two short salient curves, *g g*, and longer re-entering 40 curves *h h*. The head or stock E D has running along its entire margin or profile, both on the front and back, a thread, *i i*, which is continued across its lower part, immediately above *e*, in an approximately semicircular curve. Below *e* the shank is ornamented on both the 45 front and back, as shown at *j*, and above *b* it is ornamented on both sides, as shown at *k*. The head E D has within the lower curved

part of the thread *i*, both on the front and back, ornamentation *n*. Within the upper 50 part, D, there is, on each side, an arched ornamentation, *p*, below which is a transverse bar-like ornamentation, *l*. On the front side there is, below the arched ornamentation *p*, a fan-like ornamentation, *m*, which intersects the ornament *l*. On the front there is, above the ornament *n*, the representation of a crane and bulrushes, as shown in Fig. 1. 55

What I claim is—

1. The design and configuration of the spoon 60 or fork, consisting, essentially, in the continuity of the curved outline of the outer edge of the bowl or body across the back of the shank, substantially as shown at *a a*, Figs. 2 and 4, and herein described. 65

2. The design and configuration of the spoon or fork, consisting in the striated bead-like projection *b*, and the continuity of the curved outline of the outer edge, *a a*, of the bowl or body below the said striated bead-like projection, all substantially as shown, and herein described. 70

3. The design and configuration of the head of the handle, consisting, essentially, of the profile form indicated by the letters *i f g h d*, 75 and herein described.

4. The design and configuration of the ornamentation of the handle indicated by the letters *i e j*, and herein described.

5. The design and configuration of the ornamentation of the handle, indicated by the letters *l p*, and herein described. 80

6. The design and configuration of the ornamentation of the head of the handle, indicated by the letters *l p m*, and herein described. 85

7. The design and configuration of the ornamentation of the stem at its junction with the body or bowl, indicated by the letters *b k*, as herein described.

8. The design of the crane and bulrushes on 90 the handle, as shown in Fig. 1, and herein described.

LE ROY S. WHITE.
